UNITED STATES PATENT OFFICE.

HERBERT E. FISK, OF NEW YORK, N. Y.

TIE SPOOL.

Application filed September 11, 1924. Serial No. 737,179.

To all whom it may concern:

Be it known that I, HERBERT E. FISK, a citizen of the United States, residing at New York, in the county and State of New York, United States of America, have invented certain new and useful Improvements in Tie Spools, of which the following, taken in connection with the accompanying drawing, is a specification.

This invention has for its object the provision of a simple form of spool or holder upon which a scarf or necktie may be wound when not in use, in order to maintain the form, shape, and size of the article and to place the same under stretching tension in order to eliminate wrinkles and restore the article to its original smoothness after use thereof, thus maintaining the characteristics of the materials used in the manufacture of such articles.

Such a device of an effective character is a great desideratum because of the increased cost of well designed and manufactured scarfs, which are generally accepted, necessary accessory of dress. The improved appliance hereinafter illustrated and described embodies the structure essential to carrying into effect the above requirements, and is free from objections and disadvantages to which earlier devices of this character have been subject by reason of their complicated construction, ungainly appearance and inefficient operation.

The various features of my invention will be illustrated and described fully in the accompanying drawings and specification, and pointed out in the claim.

Referring to the drawings:—

Figure 1 is a view in side elevation of a tie spool in the construction of which my improvements have been embodied.

Figure 2 is a view thereof in elevation looking from left to right, and

Figure 3 is a similar elevation looking from right to left.

Figure 4 is a transverse section on the line 4—4 of Figure 1.

Figure 5 is a perspective, upon a smaller scale, showing the device in use with a scarf wound thereupon.

In the illustrated embodiment I have shown a tie spool comprising a bifurcated member 1, preferably formed as an integral structure of some such material of attractive appearance as wood, preferably white ash or maple, or bakelite, ivory, or bone,

having a head 2 from which extends resilient blades 3 and 4, preferably round exteriorly, and formed with a slight spring or arch as indicated at 5 to afford sufficient space therebetween for reception of a portion of the scarf, tie or similar article to be wound thereon, it being understood that the appliance may be used for lace, ribbons, or in general in any field for which it is adapted by the nature of my improvements.

I prefer to form the ends of the blades somewhat as shown at 6 and 7 respectively, with beveled portions 8 to facilitate introduction of the article to be supported.

In operation the tie spool is held in one hand by the head or grip 2 and the article to be supported, as for example the scarf 9 shown in Figure 5, is inserted edgewise between the ends 6 and 7 until the forward edge of the tie or scarf has reached the most inwardly end 10 of the opening between the prongs or blades, the tie resting flatly therebetween.

Then the scarf is pulled until one of its ends is flush with the side of the opening and the operator then presses the blades between the thumb and forefinger until the inside surfaces of the blades are in contact with both surfaces of the scarf, thus gripping the scarf firmly but without damage thereto, owing to the manner in which the surfaces are designed to contact with the scarf.

Then the user begins to wind the scarf upon the outer surface of the tie spool in the recessed portions of the top and bottom blades, winding the wider ends of the scarf straight around and distributing the narrow portion at the center of the scarf from left to right after the manner of usual spool winding.

The scarf having been completely wound upon the tie spool, an elastic band is preferably placed thereon as indicated at 11, and the scarf is subjected to a yielding tension, due to the expansion of the blades therewithin, sufficient to eliminate wrinkles and crevices, and to restore the original form and shape of the scarf, a notable advantage of the appliance being that when used diligently with a new scarf, the appliance prevents the formation of permanent wrinkles and thus retains the fresh appearance of the scarf.

The device thus used may be placed in

a drawer, traveling bag, or elsewhere, occupying but little space, and presenting an attractive appearance, and when the scarf is desired for use it may be removed readily from the appliance by a reversal of the above described operation.

Having illustrated and described my invention and suitable means for carrying the same into effect, it will be understood that I do not limit myself to the specific materials and structure specified, nor in general otherwise than as set forth in the claim read in connection with this specification.

I claim:—

15. A holder for scarfs and the like comprising a bifurcated member having sub-

stantially parallel blades presenting toward each other broad surfaces, one of said blades being arched in the direction of its length, and adapted to receive therebetween 20 a portion of a scarf or similar article, the remainder of which is wound peripherally about said blades in such a manner as to place the same under tension, and in combination therewith means to maintain said 25 tension and to prevent slippage of the portions of said article upon each other under the expansive strain of the aforesaid blades.

In testimony whereof, I have signed this 30 specification.

HERBERT E. FISK.
